UNITED STATES PATENT OFFICE

JULIUS W. LILLY, OF BINGHAMTON, NEW YORK.

DESIGN FOR INKSTANDS.

Specification forming part of Design No. **11,426**, dated September 23, 1879; application filed August 18, 1879.
[Term of patent 7 years.]

To all whom it may concern:

Be it known that I, JULIUS W. LILLY, of Binghamton, in the county of Broome and State of New York, have originated and invented a new and useful Design for Inkstands; and I do hereby declare that the following is a full, clear, and exact description thereof, reference being had to the accompanying drawings, forming a part of this specification.

Figure 1 of the drawings is a plan view of my inkstand, and Fig. 2 is a side elevation view of the same.

In the drawings, A designates a hexagonal-shaped base of the cylindrical ink-reservoir *a*, and B a pen-rack secured upon the base A. Upon the top and sides of the base A are a series of V-shaped grooves, C, which radiate from the cylinder *a* to the upper rim of the base A, and thence down the sides of the same, thereby subdividing the six sides of said base A into twelve plain surfaces or squares, *d*. E designates six recesses formed in the top of

the base A, each recess intersecting a groove, as shown.

What I claim as my design is—

1. The cylindrical reservoir *a*, hexagonal-shaped base A, and the V-shaped grooves C, radiating from the cylinder *a* to the upper rim of the base, and thence down the sides of the same, six of the said grooves being intersected by the recesses E, substantially as set forth.

2. The base A, hexagonal in shape, the cylinder *a* upon the same, and the V-shaped grooves radiating from the cylinder to the rim of the base, and also extending down the sides of the same, as shown and set forth.

In testimony that I claim the foregoing as my own I affix my signature in presence of two witnesses.

JULIUS W. LILLY.
